RECORD SHAVING MACHINE

Charles Huenlich, Bloomfield, N. J., assignor to
 Thomas A. Edison, Incorporated, West Orange,
 N. J., a corporation of New Jersey

Application February 20, 1937, Serial No. 126,778

13 Claims. (Cl. 82—1.1)

This invention relates to machines for shaving sound records, and more particularly to the control of the record-engaging tool for performing the shaving operation.

5 Sound record cylinders are made of wax-like material and when used in connection with business phonographs, it is customary, after dictated material has been recorded on the cylinder and the record transcribed, to resurface the cylinder by shaving off the outer surface portion thereof so as to prepare it for receiving a new record thereon. Such a cylinder is commonly referred to as a "used" record, but it is also customary to shave off the outer surface portion 10 of a new cylinder to provide the same with a smooth properly prepared surface to be recorded upon. Therefore, the term "record" as used herein connotes a wax or other tablet having a surface either adapted to receive and bear or 15 already bearing a sound track.

The resurfacing operation requires a shaving knife mounted on a carriage and adapted to transverse a rotatably mounted record cylinder and to be held in operative relation with respect 20 thereto. Means are provided for setting the knife within fixed limits so that it will take a cut of desired depth as the cylinder is rotated. To avoid injury to the cylinder as well as the knife, the knife setting operation should be performed when the cylinder is not rotating. It is 25 therefore essential to stop the rotation of the cylinder whenever the knife is adjusted to operative position with respect to the record, or whenever it is desired to remove the cylinder 30 from the machine.

It is an object of the present invention to provide in a record resurfacing machine, means for automatically releasing the record-engaging tool from its adjusted position as an incident to stopping the rotation of the cylinder.

Another object of the invention is to provide means whereby the automatic release of the record engaging tool may be effected at any given point of travel when operatively positioned with 45 respect to the cylinder.

A further object of the invention is the provision of a switching mechanism which electrically controls the operation of a motor for rotating the cylinder support and mechanically restores the shaving knife to its inoperative or unset position, said functions being incidental to each other.

Other objects and structural features of the invention will be hereinafter more fully described 50 and claimed.

I have illustrated an embodiment of my invention in the accompanying drawings which form a part of the specification. Referring to the drawings:

Figure 1 is a plan view of a conventional form 5 of record resurfacing machine to which my invention has been applied;

Figure 2 is a right-hand end view of the machine of Figure 1, a portion of the cabinet being shown in section;

Figure 3 is a cross sectional view taken along the line 3—3 of Figure 1;

Figure 4 is a cross sectional view taken along the line 4—4 of Figure 1;

Figure 5 is a cross sectional view taken along 15 the line 5—5 of Figure 2, showing particularly the mounting and means for retaining the adjustment of the resurfacing tool;

Figure 6 is a fragmentary view showing a 20 modification of the invention; and

Figure 7 is a cross sectional view taken along the line 7—7 of Figure 6.

With reference to Figures 1 and 2, it will be seen a base plate 1 is mounted on the cabinet 2 of a shaving machine. On the base 1 there is 25 provided left-hand standards 3 and 4, right-hand standards 5 and 6, and central standard 7. A conically-pointed stud 8 is provided in the standard 3 for engaging a recess in the left end of a mandrel shaft 9, thus providing a thrust 30 bearing for said shaft end. The shaft 9 passes through an oversize hole 10 in the standard 7 and a collar 11 secured thereon prevents the shaft from being completely disengaged from stud 8. The shaft 9 comprises a portion of the mandrel 35 12, onto which may be slid a sound record cylinder A into frictional engagement with said mandrel, by virtue of both the mandrel 12 and the bore of the record A, being complementarily tapered. Thus far described, it will be appreciated that the mandrel is retained in an approximate position only, the oversized hole 10 and collar 11 failing to provide the definite axial alignment which is imperative during the resurfacing operation. Therefore, to maintain proper axial 40 alignment of the mandrel during rotation, a supporting means is provided which is removably associated with and adapted to engage the free end of the mandrel. This includes the swinging end-gate 15 carrying an adjustable conical stud 50 16 adapted to engage a recess in the adjacent end of the mandrel 12. The gate 15 is pivoted to a boss 17 formed on the base plate 1, and is closed, as illustrated in Figure 1, by clockwise rotation about its pivot until its forward ex-

55

tremity impinges against the right-hand extremity of the front guide rail 18. More specifically, this pivoting means comprises the post 20 extending from the boss 17 as shown in Figure 4; said post being adapted to serve as a journal for the gate and to support an inverted cup 20' within which is provided a strong torsion spring 21 normally urging said gate counterclockwise or away from the position shown. With the gate 10 adjusted to closed position mandrel 12 is wholly supported by the studs 8 and 16, the latter providing axial alignment and also preventing appreciable end play thereof. To retain the gate in closed position there is provided a latch 25, which 15 is pivotally secured by means of a long shank 27 to a vertical post 26 swivelling in guide rail 18; the shank 27 swings in a horizontal slot 28 in the rail 18. The most rearward contemplated adjustment of this latch is that illustrated in Figure 1, wherein its shank 27 protrudes through a 20 slot 15' in the forward extremity of the gate 15. The latch 25 retains this adjustment, until deliberately moved, by virtue of a spring-catch member 29, which, as is well known in the art, 25 surrounds the shank 27 and is normally urged toward the pin 26 by an internal spring (not shown) disposed about said shank. The process of disengaging the right end support from the mandrel consists in pulling forward on the knob 30' of latch 25, whereupon the catch member 29, compressing its spring, moves slightly toward the knob 25' and permits the latch to swing about its pivot 26 to a more clockwise adjustment, disengaging the gate 15; the latter is thereupon 30 swung in a counterclockwise direction to an open position. The reverse process of engaging the right end support with the mandrel consists in first adjusting the gate to a closed position and then moving the latch 25 to the illustrated gate-engaging position.

When the right end support for the mandrel 12 is operatively positioned as above described, said mandrel is in turn parallel relation with the guide rail 18 and thus the record may be rotated for resurfacing. In the illustration of Figure 3, the driving means includes a motor M mounted within the cabinet 2 and having a driving pulley m adapted to drive, by means of the belt 22, a pulley 23 carried by the mandrel shaft 9; there being provided in the base plate 1 a suitable slot 24 permitting the free passage of the belt 22 from motor M to the pulley 23.

The resurfacing machine illustrated is adapted to shave a thin layer from the outer surface 55 of the cylinder by means of a record-engaging tool illustrated herein as a knife 30. The knife 30 is secured to the end of a bar 31, which is adjustably mounted in a boss 32' formed upon the movable arm 32 which latter is sometimes hereinafter called the tool carriage. This carriage is slidably and partially rotatably mounted on the carriage rod 35, the latter being disposed behind and parallel to the mandrel 12 and terminally secured to the standards 3 and 5. The 60 arm 32 is approximately semicircular in side elevation, and is provided with a smooth flat surface 33 at its forward extremity. A weight 34, formed integrally with the arm 32, provides a convenient handlepiece normally maintaining the 65 surface 33 in contact with the top surface of the front guide rail 18. The knife 30 may be so adjusted that when the arm 32 is in the position illustrated by Figure 2, the knife will engage the 70 surface of the record A to the desired depth. 75 Whether or not the knife 30 is adjusted, the arm

32 may always be lifted to rotate the entire assembly including said knife and parts connected thereto in a clockwise direction, thereby disengaging the knife from the surface of the record if said knife be in set position.

The carriage, including its associated parts such as the knife 30, is designed to traverse the record surface during rotation thereof. To this end there is provided a feed screw 36 parallel to carriage rod 35 and journaled in standards 4 and 6. The feed screw 36 is rotated during mandrel rotation by a belt 37 engaging pulley 38 carried by said screw and a driving pulley 29 carried by the mandrel shaft 9. A feed nut 40 is arranged to engage the feed screw when the arm 32 occupies its normal resting position on the guide rail 18, and to disengage the same when the arm 32 is lifted; said feed nut is secured to the carriage 32 through the medium of a slightly resilient extension 41 carried by the portion 40' formed on said carriage. It will therefore be understood that when the knife 30 is in a set or cutting position and the mandrel 12 is rotated, the carriage 32 and hence the knife 30 will move steadily in a longitudinal direction of the cylinder 25 from right to left, thus taking a uniform cut from the outer portion of the record surface. For confining the shavings from the record surface there is provided a chip deflector 42 carried by the knife bar 31, and a chip chute 42' for directing the chips into a suitable receptacle (not shown) within the cabinet 2.

The construction described above is generally known to the art; it is also conventional to provide an electrical switch for controlling the mandrel rotating means. Such a switch, indicated by the reference character 145, may be of the well known commercial type wherein a spring actuated toggle lever system is controlled by an outwardly extending arm 146 movable to an "On" 40 and an "Off" position to close and open, respectively, an electric circuit. Such a circuit is shown in Figure 3 which serially includes the motor M and any suitable source of electrical power therefor, such for example as the schematically illustrated "supply line" terminals 144. Associated with the switch are indicia which may be carried upon the side wings 146' of the lever 146 (see Figure 4) for indicating its operated position. In the present embodiment I mount the 45 switch 145, by means of the screws 145', below the top of the cabinet 2 at a point adjacent to the right-hand end of the guide rail 18, and with its controlling arm 146 projecting through an opening 2' sufficiently large to permit the angular 50 movement of the arm and the viewing of the indicia which connote its position.

According to my invention the adjusting means for the shaving knife 30 is so interrelated with the mandrel rotating or driving means that the 60 rendering of said latter means inoperative renders said adjusting means ineffective and causes the release of the knife 30 from the record surface. To this end I provide mechanisms connected to or associated with the arm 146 and operatively movable therewith for effecting control over the knife adjusting means, which means will now be fully described.

The knife bar 31 is slidably mounted in opening 43 of the boss 32'. A guide rod 44, located above and parallel to the knife bar 31, extends through and beyond the boss 32'; the rod also passes through a sleeve 45, secured in the upper end of said boss by a forced fit therewith. The rod 44 has a reduced threaded upper end portion 70 75

44' which extends through the top wall 49 of the cap 47, and the rod is secured to the cap by means of a cylindrical member 48 threaded onto the said end portion of the rod. The upper end portion of the sleeve 45 provides a seat for the lower end of a coil spring 46 disposed about the rod 44, said spring at its opposite upper end abutting against the top wall of the cap 47. The skirt of the cap 47 is of such length and design as to 5 cover the spring 46 in all positions of the knife bar 31 and move freely over the boss 32'. The upper end of the knife bar 31 extends through an aperture in the wall 49 and is surmounted by an enlarged head 50 which prevents the movement 10 of the bar toward the record unless the cap 47 is also moved in that direction. Since the coil spring 46 is biased, the principal function of this spring is to return the cap 47 and thereby the knife bar 31 to inoperative position with the knife 15 bar out of engagement with the record cylinder when the knife bar locking mechanism (hereinafter described) is loosened. A collar 52 is adjustably mounted, by means of a set screw, upon the knife bar 31 at a point slightly above the upper end of 20 the boss 32', said collar providing a seat for the lower end of a compression spring 53 disposed about the bar 31 and having its upper end abutting 25 against the top wall 49 of the cap 47.

The member 48, in addition to securing the 30 guide rod 44 to the cap 47, also constitutes a finger piece or manipulative member whereby the knife bar 31 may be moved to bring the knife 35 to operative position. When the parts are thus moved the engagement of the knife with the surface of the record will be cushioned by means of the spring 53, and proportionally, as will be understood, the depth of the engagement of the knife with the record will be determined by the amount of force applied to move the rod 44 down 40 against its spring 46. To lock the knife in a set or operative position I may employ the construction about to be described.

The boss 32' is provided with a cylindrical opening 55 extending transversely therethrough, 45 the axis of said opening preferably intersecting the axis of knife bar 31, as clearly shown in Figure 5. Slidably disposed within the opening 55 is a cylindrical stud pin clamping member 56 having a cylindrical transverse opening 57 through which the knife bar 31 extends. Opening 57 is slightly larger than, or oversized with respect to the knife bar so that when the two are concentrically positioned the knife bar may slide freely through said opening. The left-hand portion of member 56, as viewed in Figure 5, is reduced and extends through a correspondingly reduced portion of opening 55 and outwardly from the boss 32' a considerable distance. The outer end portion of member 56 has a cylindrical headed nut 58 threaded thereon, the head 58' of the nut being adjacent the side of the mounting 32'. A manually operative lever 60 is provided at its lower end with two spaced flanges 61 and 61' by means of which it is pivotally mounted on the 60 reduced portion of the nut 58. A split collar 63 is firmly clamped on nut 58 between the flanges 61 and 61' of the lever 60 by means of a screw 64 threaded through opposed sections 65 and 66 of the collar. The section 66 has an extension arm 67 by which the collar 63 may be actuated in a counterclockwise direction as will be hereinafter described. A torsion spring 68 furnishes a resilient connection between the lever 60 and the collar 63 by having its intermediate portion disposed or coiled around the head of the nut 58

and the ends thereof respectively engaging the section 66 and the lever 60. By this arrangement if the lever 60 is moved in the direction of the arrow B in Figure 2, movement in the same direction will be transmitted through said spring 5 to the collar 63 and nut 58.

To securely lock the knife bar 31 after it has been operatively positioned, lever 60 is merely moved in the direction of the arrow B, which movement, as just described, effects the turning 10 of the nut 58 on the reduced threaded portion of the member 56. In the turning of the nut thus effected, the head 58' thereof coacts with the side of the boss 32' to move the member 56 longitudinally to the left (see Figure 5) in the opening 15 55 to a position in which the opening 57 in said member is eccentric to the knife bar 31, and the wall of the opening 57 is forced against the knife bar 31 so as to hold the latter in a set position, the spring 68 being of sufficient strength to 20 transmit the force necessary to thus effect the firm gripping of the knife bar by the member 56. It is apparent that the maximum pressure with which member 56 can be so engaged with the knife bar is determined by the strength of the 25 spring 68. To prevent too great a movement of the lever 60 in a clockwise direction and thus impart an over pressure on the extension arm 67 of the split collar 63 through the means of the spring 68, I provide the stationary pin or stop 69 on the 30 side of the mounting 32'. The movement of the lever 60 is thus limited to an extent of giving the proper pressure on the collar to clamp the knife bar 31. For automatically releasing the knife bar, and thus release the knife from its engagement 35 with the record, I employ the mechanism about to be described.

Referring particularly to Figures 2 and 4, it will be seen there is provided a bell-crank lever 70 pivotally mounted on a rear projection 32" of 40 the carriage 32 by means of a shoulder screw 71. The upper arm 72 of the bell-crank extends beneath the arm 67 of the split collar 63, while the lower arm 73 thereof extends downwardly and inwardly, terminating in a laterally extending 45 finger 74 adapted to overlie closely a bar 75 (see Figure 2). The bar 75 is adapted for parallel movement in a vertical direction by virtue of its being supported at its ends by means of parallel motion links 76 and 77. These links are adapted 50 for pivotal movement at their lower ends, by means of the shoulder screws 76' and 77' threaded into the base plate 1, and at their upper ends by similar screws threaded in the shanks of spacing rivets 78 and 79 secured to the bar 75, as may be 55 best seen in Figure 1. To provide means for effecting the movement of the bar 75 the right-hand end thereof has a projection or plate 80 extending forwardly and downwardly to a position 60 slightly below the plate 1.

At the right-hand end of the plate 1, below the surface thereof, I provide supporting members 82 and 83, which are secured to said plate by screws 82' and 83', respectively (see Figure 2). Journaled in said supports is a shaft 85, carrying at its 65 forward end a crank member 86 which projects, through a slot 87, outwardly and forwardly of the cabinet, and is adapted to engage, by means of a socket portion 88, the upper end of the switch arm 146. The socket portion 88 fits fairly snugly 70 over the end of the arm 146, and affords a ready grip for an operator to grasp and move it to cause the arm 146 to effect the "On" and "Off" positions of the switch 145. Secured to the shaft 85 as by means of the collar 85' is an upstanding arm 90, 75

which carries at its upper end a one-way pawl 92 pivoted on pin 91 and adapted to coact with the adjacent lower end of plate 80. The pawl 92 is normally pivotally held in a given angular position by virtue of an angular lug 93 abutting against the arm 90, said lug being retained in such position by the tension of a pull spring 94 having one of its ends attached thereto and the other end secured to a lug 95 carried by said arm (see Figures 2 and 4). The arm 90 may be adjusted in angular position on the shaft 85 by means of the set screw 90', the adjustment being such that when the switch arm 146 is in the "On" position the nose or engaging end of the pawl 92 is a slight distance from the plate 80, as seen in Figure 4. It is apparent, therefore, that if the switch arm 146 is moved by means of the crank member 86 from the "On" position shown in Figure 1 to the "Off" position, the shaft 85 and arm 90 will be similarly rocked, thereby causing the pawl 92 to travel in an arc from the position which it occupies in Figure 4 to the position wherein it is shown in dotted lines. Upon such movement it will be obvious that the nose 92 of the pawl will shortly engage the adjacent plate 80 of the bar 75 and move this latter sidewise and simultaneously upward due to the arrangement of supporting links 76 and 77. As a result of such upward movement of the bar 75, the bell-crank lever 70 will be turned about its pivot 71 to cause its upper arm 72 to engage the extension 67 of collar 63, and thus release the knife bar 31 through the mechanism already described. When the knife bar is thus released to disengage the knife, said bar moves upwardly under the tension of the spring 46 until the movement thereof is arrested by the adjustable collar 31' secured to said bar at the front of the boss 32'. Also, to prevent angular movement of the bar within its opening 43, there is provided a small bracket 31'' screwed to the under side of the boss 32' and adapted to engage a groove in the bar as seen in the detailed view of Figure 5.

As stated, the finger 74 of the bell-crank 70 is always adapted to overlie closely the edge of the bar 75, so that the upward movement thereof will always rock said bell-crank to effect the release of the knife 30 at any point as it traverses the record. However, it may become desirable at times to cause the release of said knife to be effected only at a given point in its longitudinal travel, such for instance as when the knife has reached a position near the end of its travel, or is in a position past the extreme end of the cylinder. To provide for such a contingency, I make the bell-crank 70 interchangeable with another crank 70' shown in Figure 6. The crank member 70' has all of the essentials of the crank 70 except that its lower arm 73' is shorter by an amount equivalent to the distance of the upward movement of the bar 75. Consequently, the finger 74' will overlie the bar 75 at such a spaced distance therefrom as not (in the absence of other means) to be affected by the movement of said bar. Under such conditions, to effect the release of the knife 30 at a given point in its travel, I provide a sliding block member 100 adapted to be set, as by means of the set screw 101, at any desired or predetermined point along the edge of the bar 75. For instance, if it is desired to release the knife at the terminal point of its travel, said member may be set, as shown in Figure 6, near the extremity of said bar. If it is desired to release the knife at any intermediate point in its travel, the member 100 may be advanced along

the bar 75 to the selected point, as indicated by the dash and dot lines.

While I have described a preferred embodiment of my invention it is to be understood that the same is subject to changes and modifications without departure from the spirit of the invention or the scope of the appended claims. 5

What I claim is:

1. In a record shaving machine, the combination with a rotatable support for a record to be shaved, of a motor for rotating said support, a switch for controlling said motor, a record-engaging tool, means for locking said tool in operative position with respect to the record, and means operative automatically as an incident to 15 the stopping of the motor by the manipulation of said switch for releasing said tool.

2. In a record shaving machine, the combination of a mandrel for supporting a record to be shaved, a record-engaging tool, means for setting 20 the tool in operative position with respect to the record supported by said mandrel, a motor for rotating said mandrel, a switching mechanism for controlling said motor, and means comprising a part of said switching mechanism for 25 releasing the tool as an incident to the stopping of the motor.

3. In a record shaving machine, the combination with a rotatable support for a record to be shaved, of a motor for rotating said support, a 30 switch for controlling said motor, a record-engaging tool, means for setting said tool in operative position with respect to the record, means for effecting the release of said tool from operative position, and means common to said switch and 35 said knife releasing means for stopping the motor and releasing said tool.

4. In a record shaving machine, the combination with a rotatable support for a record to be shaved and a carriage mounted for relative feeding movement, of a record-engaging tool on said carriage, means for locking said tool in operative position with respect to the record, a motor for 40 rotating said support, a switch therefor, and means operable automatically as an incident to 45 the stopping of the motor by the manipulation of said switch for releasing said tool to inoperative position at any point of travel of the carriage.

5. In a record shaving machine, the combination with a rotatable mandrel for supporting a 50 record to be shaved and a carriage mounted for relative feeding movement, of a record-engaging tool on said carriage, means for setting said tool in operative position with respect to the record, and means for effecting the release of said tool 55 from operative position, said means comprising a switch mechanism adapted to control the rotation of said mandrel and as an incident thereto effect the release of said tool to an inoperative position.

6. In a record shaving machine, the combination with a rotatable support for a record to be shaved, of a motor for rotating the support, a switch for controlling said motor, a shaving knife, means for setting said knife with respect to the 65 record, and an actuating device for effecting the release of said knife to an unset position, said device being conditioned to function by the operation of said switch in starting said motor, and caused to function by said switch as an incident to 70 the stopping of the motor.

7. In a record shaving machine, the combination with a rotatable support for a record to be shaved, of a switch, a circuit including said switch and a motor for rotating said support, said cir- 75

cuit being opened and closed by the operation of said switch to opening and closing positions, a shaving knife, means for setting said knife with respect to the record, and an actuating device for effecting the release of said knife, said device being conditioned to function by the movement of said switch to a circuit closing position and caused to function by the movement of said switch in opening said circuit.

10. 8. In a record shaving machine, the combination with a rotatable mandrel for supporting a record to be shaved and a carriage mounted for relative feeding movement, of a record-engaging tool on said carriage, means for locking said tool in operative position with respect to the record, a motor for rotating said mandrel, and a switch mechanism adapted to make or break a circuit through said motor and as an incident to the manipulation of said switch mechanism substantially 15 simultaneously effect the release of said tool to inoperative position.

9. In a record shaving machine, the combination with a rotatable support for a record to be shaved and a carriage mounted for relative feeding movement, of a record-engaging tool on said carriage, means for locking said tool in operative position with respect to the record, a motor for rotating said support, and a switch for the circuit of said motor, said switch when actuated to a 20 circuit closing position starting the motor and resetting a control mechanism for releasing said locking means and when actuated to an opened circuit position substantially simultaneously stopping said motor and operating said control 25 mechanism to effect the release of said locking means.

30. 10. In a record shaving machine, the combination with a rotatable record support, of means for

driving said support, means for controlling said driving means, a record-engageable tool, means for locking said tool in operative position with respect to the record, means operable to effect the release of said tool, and means whereby the operation of one of the said controlling and releasing means is effected as an incident to the operation of the other.

11. In a record shaving machine, the combination with a rotatable record support, of means for driving said support, means for controlling said driving means, a record-engageable tool, means for locking said tool in operative position with respect to the record, and means operable automatically as an incident to the operation of 15 said controlling means to effect the release of said tool.

12. In a record shaving machine, the combination with a rotatable record support, of means for rotating said support, means operable to effect 20 the stopping of said support, a record-engageable tool, means for locking said tool in operative position with respect to the record, means operable to effect the release of said tool, and means whereby the operation of one of the said stopping and 25 releasing means is effected as an incident to the operation of the other.

13. In a record shaving machine, the combination with a rotatable record support, of means for rotating said support, means operable to effect 30 the stopping of said support, a record-engageable tool, means for locking said tool in operative position with respect to the record, and means operable automatically as an incident to the operation of said stopping means to effect the release 35 of said tool.

CHARLES HUENLICH.

CERTIFICATE OF CORRECTION.

October 12, 1937.

Patent No. 2,095,332.

CHARLES HUENLICH.

It is hereby certified that error appears in the printed specification of the above numbered patent requiring correction as follows: Page 1, first column, line 23, for the word "transverse" read traverse; line 35, for "form" read from; and second column, line 43, for "falling" read failing; page 2, first column, line 43, for "turn" read true; and that the said Letters Patent should be read with these corrections therein that the same may conform to the record of the case in the Patent Office.

Signed and sealed this 21st day of December, A. D. 1937.

Henry Van Arsdale,
Acting Commissioner of Patents.
